ASH TRAY

Stephen M. Quigley, Baldwin Township, Allegheny County, Pa., and Daniel Goodman, Sherman Oaks, Calif.

Application February 24, 1953, Serial No. 23,765

Term of patent 14 years

(Cl. D85—2)

To all whom it may concern:

Be it known that we, Stephen M. Quigley and Daniel Goodman, citizens of the United States, residing at Baldwin Township, in the county of Allegheny and State of Pennsylvania, and Sherman Oaks, in the county of Los Angeles and State of California, have invented a new, original, and ornamental Design for an Ash Tray, of which the following is a specification, reference being had to the accompanying drawing, forming a part hereof.

Fig. 1 is a top plan view of an ash tray, showing our new design; and Fig. 2 is a perspective view thereof.

The ash tray shown in the accompanying drawings is made of glass, with the result that the inner edge of the peripheral flange and the edge of the base portion appear as thin lines

visible through the glass in Fig. 1. The dotted lines appearing in the fabric base portion of Fig. 2 indicates stitching in the fabric.

We claim:

The ornamental design for an ash tray, substantially as shown and described.

STEPHEN M. QUIGLEY.
DANIEL GOODMAN.
